UNITED STATES PATENT OFFICE.

FRANK J. KOTZICH, OF CHICAGO, ILLINOIS, ASSIGNOR TO A. STEIN & COMPANY, OF CHICAGO, ILLINOIS, A CORPORATION.

MACHINE FOR SHAPING METAL.

1,288,037.

Specification of Letters Patent. Patented Dec. 17, 1918.

Application filed February 24, 1916. Serial No. 80,130.

To all whom it may concern:

Be it known that I, FRANK J. KOTZICH, a subject of the Emperor of Austria-Hungary, residing in Chicago, county of Cook, and 5 State of Illinois, have invented certain new and useful Improvements in Machines for Shaping Metal, of which I do declare the following to be a full, clear, and exact description, reference being had to the accompanying drawings, forming a part of this specification.

My present invention, while preliminarily designed to provide a machine for forming clasps of metal preferably covered with a 15 fabric (a sample of this type of clasp being shown in Letters Patent No. 1,199,191, dated September 26, 1916) is susceptible of a much wider application for the manufacture of various other articles. The invention consists in the novel features of construction hereinafter described, illustrated in the accompanying drawings and particularly 20 pointed out in the claims at the end of this specification.

25 Figure 1 is a front view of a machine embodying my invention. Fig. 2 is a perspective view showing a metal strip covered with fabric from which blanks, to be subsequently bent, may be cut. Fig. 3 is a perspective view showing a blank that has been cut and bent by my machine. Fig. 4 is a view on an enlarged scale in vertical section on line 4—4 of Fig. 1. Fig. 5 is a view in vertical section similar to the left-hand portion of Fig. 4 but showing parts in elevation. Fig. 6 is a detail perspective view of a plunger for ejecting the finished blanks from the machine. Figs. 7, 8, 9, and 10 are detail views in front elevation showing more 30 particularly the dies and die actuating mechanisms in different positions the cover plate being removed. Fig. 11 is a view partly in section and partly in plan, on line 11—11 of Fig. 1. Fig. 12 is a detail view in vertical section on line 12—12 of Fig. 1. Fig. 13 is a detail view in vertical section on line 13—13 of Fig. 1. Fig. 14 is a view in vertical section on line 14—14 of Fig. 1.

50 A designates the main standard of the machine that is formed preferably of cast metal and is provided at its upper end with an ex-

tension a. Through the top of the standard A and through its extension a passes a shaft B, preferably encircled by a suitable bearing sleeve b. Upon one end of the shaft B 55 is loosely mounted a drive pulley B' and between the adjacent end of the standard A and the pulley B' is placed a suitable clutch whereby the pulley B' may be thrown into and out of gear with the shaft B. As shown, 60 the clutch consists of a sleeve C that is fixed to the shaft B, this sleeve carrying a spring-actuated pawl c, this pawl c being normally forced toward engagement with teeth formed upon the adjacent end of the hub of 65 the pulley B'. In the sleeve C is formed an annular groove c' within which projects a pointed or cam-shaped arm c² the end of which is adapted to enter a slot c³ in the pawl c and thus retract the pawl when it is desired to disengage the pulley B' from the sleeve C. The arm c² is carried upon the upper end of the rod c⁴ that is forced normally upward by a coil spring c⁵. As the clutch forms no part of my present invention, 70 I do not deem it necessary to describe it at greater length, it being sufficient to say that when the rod c⁴ is drawn downward (as by a treadle) the arm c² will be moved downward in the annular groove c' of the sleeve C 75 below the notch c³ of the pawl c and thus will allow the pawl c to lock the pulley B' to the shaft B. To the end of the extension a is fastened, as by screws d, a supporting plate or bracket D having at its lower end an outwardly projecting flange d' and having its lower portion extended laterally, as shown in Fig. 1, to support the feed mechanism and adjacent parts.

Between the outwardly projecting portions d² and d³ of a block or plate D' (see Fig. 11) secured to the front of the plate or bracket D is mounted the die mechanism by which the blanks will be bent. The precise character of this die mechanism may be 90 varied in keeping with the kind of work to be done, but I have shown the die mechanism as comprising dies adapted to bend blanks to the form shown in Fig. 3 of the drawings. Each of these blanks comprises a U-shaped 100 body portion E with inwardly folded ends e. The blank may be formed of a strip of

metal E' having a covering e' of fabric, as illustrated in Fig. 2, the edges of the fabric being secured together and preferably to the face of the metal strip by glue or other adhesive material.

Upon the flange or shelf d' of the plate D is mounted a female die F that may be held in place by a pin f (see Fig. 4) and this die is formed with a central recess f' to receive the blank as its final bending is effected. Each of the side walls of the female die F is formed at its top with a seat f² and with a shoulder f³, the purpose of which, as clearly shown by Fig. 8, is to co-operate with portions of the male die in effecting the initial folding of the edges e of the blank E.

Above the female die F is mounted a male die that is shown as consisting of a plurality of parts, viz., a central male die G for imparting a U-shaped bend to the body of the blank E, side dies g for effecting the initial folding of the edges of the blank and side dies g' for co-operating with the female die in completing the folding of the edges of the blank, as clearly shown in Fig. 10 of the drawing. A suitable cover plate y (see Figs. 1 and 11) will retain the dies within the chamber of the bracket D. The central male die G is formed with an expanded head g³ and about the upper portion of the shank of this die is set a coil spring H, the lower end of which bears upon the pin h that passes through the stem of the die G, while the upper end of the spring presses against a shouldered portion 20 (see Figs. 4 and 9) that projects forwardly from the upper part of the shank of the side dies g', it being understood that these dies g' are shown as formed at the lower end of a U-shaped body (see Fig. 11) the upper portion of which is cut away to admit the coil spring H (see Figs. 7 to 10). To the upper portion 20 of the body of the side dies g' is secured a pin 45 21 to which is pivotally connected the lower hub of a link 22, the upper end of this link being pivotally mounted, as shown in Fig. 4, upon the outer end of a wrist pin 23 that projects from a cam wheel K keyed to the outer end of the main shaft B. When the cam wheel K is revolved, the connection between the cam wheel and the upper portion 50 of the side male dies g' will cause the side male dies g' to descend and at the same time will cause the central male die G to descend because of the pressure exerted upon the stem of the die G from the coil spring H. When, however, the die G has about reached the limit of its downward movement, as shown in Fig. 9, the continued rotation of the cam wheel K will cause the side dies g' to move farther downward, the coil spring H being compressed, as shown in Fig. 10. The purpose of this relative move-

ment of the central die G and the side male dies g' is to complete the folding of the upper edges of the blank, as will hereafter more fully appear.

From the upper end of the shank or body portion of the side male dies g projects a pin carrying a roll 25 that enters a cam groove 26 in the cam wheel K. The greater part of this cam groove 26 is concentric and while the roll 25 is within this concentric part of the groove 26 no movement will be imparted to the dies g. As soon, however, as the roll 25 enters the offset or concentric portion 27 of the cam way, the dies g will be forced downward from the position shown in Fig. 7 to the position shown in Fig. 8 of the drawings. It will be assumed that when a blank E has been fed above the female die and has been severed from the strip E', the descent of the side male dies g will cause the upward turning of the edges of the blank E, as shown in Fig. 8 of the drawings, after which the continued rotation of the cam wheel K will cause the withdrawal of the dies g, as shown in Fig. 9 of the drawings. By reference more particularly to Figs. 7 to 10 of the drawings, the relative operation of the dies in forming the folded blanks will be seen to be as follows: The rotation of the cam wheel K first causes the side male dies g to descend and to co-operate with the seats f² and shoulder f³ of the female die F in bending upward the edges of the blank, as shown in Fig. 8 of the drawings. As this bending of the edges of the blank is effected and as the side male dies g are retreating, the central male die G and the side dies g' will be moved downward by the link 22, as shown in Figs. 8 and 9 of the drawings, and the central male die G will force the blank E into the central cavity of the female die and will impart a U-shaped bend to the body of the blank. After the central male die G has reached the limit of its movement, the further downward movement of the side male die g' will cause these dies to pass from the position shown in Fig. 9 to the position shown in Fig. 10 of the drawings, and in doing so they will complete the folding of the edges e of the blank E, as shown in Fig. 10.

When the blank E has been folded, as shown in Fig. 10, the continued rotation of the cam wheel K will cause the link 22 to lift the central male die G and side male dies g' to the position shown in Fig. 7 of the drawings, leaving the folded blank E in the central cavity of the female die. In order to eject the blank from the female die, I provide the mechanism next to be described and illustrated more particularly in Figs. 4 and 6 of the drawings. This mechanism comprises a plunger or ejector

M having a head *m* conforming in general outline to the shape of the female die and this head seats normally within a recess 30 (see Fig. 4) formed in the block D' that is secured, as by a screw 32, to the plate or bracket D. The stem of the plunger M passes through the block D' and plate D and has its outer end pivotally connected to a lever 35 pivotally mounted upon a bracket 36, the lower end of this lever being forced normally away from the plate D by a spring 37 (see Fig. 4). To the upper end of the lever 35 is pivotally connected a rod 38 that passes through the plate D, and the end of the rod 38 projects beneath the periphery of the cam wheel K. By reference to Figs. 5, 7 and 10 of the drawings, it will be seen that upon the periphery of the cam wheel K is formed an inclined or cam-shaped rib 39 and the purpose of this rib 39 is to contact with the end of the rod 38 and cause this rod to move backward so as to move the lever 35 and the plunger M from the position shown by full lines in Fig. 4 to the position shown by dotted lines. This operation of the ejector mechanism by the cam plate or rib 39 will occur shortly after the male dies have been retracted from the female die. When the ejector mechanism is thus operated, the folded blanks will be thrown outward through the opening y' in the front plate y (see Fig. 1). When the pin 38 escapes from contact with the cam rib or plate 39, the spring 37 will retract the plunger M to the position shown by full lines in Fig. 4.

At the feed side of the male dies is arranged a knife O, the lower sharpened end of which cooperates with a blade O' in severing the strip E' into proper lengths to form the folded blanks E. As shown, the knife O is secured to the side of the body portion of the side male dies g and the blade O' is secured adjacent the female die F. It will thus be seen that as the side male dies are moved downward in manner hereinbefore described, the severing of the blanks from the strip will be effected, and by reference to Fig. 7 of the drawings it will be seen that the severing of the strip will occur immediately before the dies come into action.

In order to direct the strip E' accurately to position over the female die E, I employ the yielding guide next to be described. As shown, this guide comprises a channel-shaped plate P having upper and lower members between which will be fed the strip E' of material from which the blanks are to be formed. The guide P is pivoted, as by means of a pin 40, to an arm 41 that is fixed upon the guide rods 42 and 43, the ends of these rods being mounted respectively in sockets formed in the side bars d² and in the bracket 45 that is fastened to and projects forward from the extension d of the plate D (see Figs. 1 and 11). By reference more particularly to Figs. 7 to 10 of the drawings, it will be seen that the lower member of the guide P extends into the path of the end of the knife O, although not quite so far as the knife O'. Hence, when the knife O descends to sever the strip E', it will force downward the strip and the free end of the guide, the guide turning about its pivot 40. In order to restore the guide and the strip to position to enable the strip to be accurately fed between the dies, I preferably employ a coil spring 50 mounted upon the rod 43, this spring having its lower end 51 extending beneath the free end of the guide P, while the opposite end of the spring is turned upward and into engagement with the rod 42 (see Figs. 1 and 14). Hence, it will be seen that after the knives O and O' have severed the strip and the knife O recedes, the spring 50 will cause the guide P to move upward and bring the free end of the strip E' into proper position to be fed between the knives 90 and the dies.

In order to feed the strip E', I prefer to employ the mechanism next to be described. Upon the rods 42 and 43 is mounted a sliding block or carrier 60 (see Figs. 1, 11 and 13 of the drawings). To the lower end of this sliding block or carrier 60 is secured, as by a screw 61, a guide 62 consisting of a block having raised portions provided with slots 63 through which will pass the strip E'. From the block 60 projects a pivot pin 65 on which is mounted a feed pawl R, the lower end of this pawl extending between the raised portions of the guide block 62 and in such position that when the block 60 is moved forward, carrying with it the pawl R, the strip E' will be advanced a distance corresponding to the travel of the block 60. A coil spring 67 mounted upon the pivot pin 65 has a bent lower end engaging the lower end of the pawl R and the bent upper end secured to the block 60, this spring serving to force the pawl R downward into engagement with the strip E'. In order to slide the block 60 back and forth for the purpose of causing the pawl R to feed the strip E', I project a pin 68 from the back of the block 60 into a slot 69 formed at the lower end of a rocking lever 70 that is pivotally mounted upon a stud 71 projecting from the front of the plate D. The upper arm 72 of the lever 70 (see Fig. 12) is provided with a pin carrying a friction roll 73 adapted to be engaged by a cam 74 formed upon the periphery of the cam wheel K. Hence, it will be seen that when in the revolution of the cam wheel K the cam 74 strikes the friction roll 73 of the upper end of the lever 70,

the rocking of the lever 70 will cause the block 60 to slide along the rods 42 and 43 carrying with it the pawl R and thus advancing the strip E' along the guideway P 5 and between the male and female dies. In order to retract the block 60 and the pawl R, I prefer to employ the adjustable spring mechanism shown more particularly in Fig. 12 of the drawings. This mechanism comprises a coil spring 75 that encircles the stud 71. The inner end of this spring 75 is secured within a socket formed in the hub of the rocking lever 70, while the outer end of the coil spring is secured within a 10 socket formed in a sleeve 76 slipped over the end of the stud 71 and inclosing the coil spring. Through the end of the sleeve 76 passes a screw 77 that enters a threaded seat in the end of the stud 71. The outer 15 surface of the sleeve 76 is preferably milled or roughened so that by turning the sleeve 76 the desired tension may be given to the coil spring 75 for properly retracting the rocking lever 70; and when the spring 75 is placed under proper tension by turning the screw 77, the end of the sleeve 76 will be 20 firmly jammed against the end of the stud 71, thereby preventing any backward movement of the sleeve 76 that would relax the 25 tension of the spring.

To prevent the backward movement of the strip E' as the feed pawl R is retracted, I have provided a check pawl S (see Figs. 1 and 11) that is pivotally mounted upon the 30 block 45, the lower end of this check pawl being arranged above a guide 62^a corresponding to the guide 62 beneath the feed pawl R. Upon the pin 80 on which the check pawl S is pivoted is arranged a coil 35 spring 81 similar to the coil spring 67 hereinbefore described, and serving to force the free end of the check pawl S downward onto the strip E' as it passes over the 40 guide 62^a.

In order to determine the extent of feed 45 imparted to the strip E' by the feed pawl R, I provide an adjusting screw 85 (see Figs. 1 and 11) that passes through a threaded hole in the block 45. In Fig. 1, the feed pawl R and the block 60 are shown at the limit of 50 their backward movement and the block 60 as contacted with the end of the adjusting screw 85 and also with a stop sleeve 86 mounted upon the rod 43 (see Fig. 18). In 55 this position, the longest feed will be imparted to the strip E', but if it is desired to feed the strip E' for shorter blanks, the adjusting screw 85 will be turned forward so as to limit the backward movement of the 60 feed pawl R.

When the metal strip E' is carried upon a reel T, I prefer to mount this reel upon a supporting arm 90 that is pivoted to a stud 91 projecting outward from the extension

of the plate or bracket D. The free end of 65 the arm 90 carries a pin 92 that passes through the head of the reel T, a sleeve 93 provided with a set screw 94 serving to hold the reel T revolvably upon the pin 92. The strip E', being coiled upon the reel T, is 70 curved and the degree of curvature of the strip is greater in that part of the strip that is coiled around the central portion of the reel. It is desirable to take the bend or curve out of that part of the strip that is nearest 75 the central part of the reel, and to this end I provide the straightening mechanism next to be described. Upon a bracket 95 (see Fig. 11) secured to the plate D are mounted a pair of straightening rolls 96 beneath which 80 the strip E' will pass and below the rolls 96 is a third straightening roll 97 that is mounted upon a stud projecting inwardly from the supporting arm 90. To the supporting arm 90 is pivotally connected the bifurcated 85 lower end of an adjusting rod 98 that passes through a sleeve 99 projecting from the bracket 95 (see Figs. 1 and 11), and upon this adjusting rod is mounted a coil spring 100 the tension of which can be adjusted by 90 means of a thumb nut 101 that is mounted upon the upper end of the rod 98. When the reel T is full, there is comparatively little curvature in the strip E' and this can be readily removed by passing the strip below the two straightening rolls 96; but as 95 the strip E' is drawn off the reel, it is found that the portion of the strip adjacent the central part of the reel is more sharply bent and to straighten this part of the strip the lower straightening roll 97 should be brought into action. The purpose of the adjusting screw 98 is to enable the lower straightening roll 97 to be brought into action automatically. Thus, it will be seen that if the tension of the spring 100 be properly adjusted for the full reel T, the rolls 96 and 97 will be separated, as shown in Fig. 1, as the initial portion of the strip is drawn from the reel; but as the strip is drawn off and the 100 weight of the reel decreases, the supporting arm 90 will rise until the straightening roll 97 is brought to bear upon the under side of the strip E' and will aid in straightening the strip.

While I have described what I regard as the preferred embodiment of my invention, it will be understood that the details of construction above set out may be varied without departing from the scope of the invention and that features of the invention may be employed without its adoption as an entirety.

Having thus described my invention, what I claim as new and desire to secure by Letters Patent is:—

1. In a machine of the character described, the combination with means for feeding a

covered metal strip and for severing it into blanks, of means for first partially bending the end portions of said blanks, means for next imparting a U-shaped bend to that part 5 of each blank between the partially bent ends to bring the edges of said ends adjacent each other, and means for finally folding inwardly the partially bent ends of the blank onto the inner face of the body of the 10 blank.

2. In a machine of the character described, the combination with means for feeding a covered metal strip and cutting it into blanks, of a central male die and side male dies arranged alongside said central male die, a female die recessed to receive said central and side male dies, and means for forcing said central and side male dies successively into said female die, said dies being 15 so shaped as to impart a U-shaped bend to the body of each blank and to fold inwardly the ends of the blank onto the inner face of said body.

3. In a machine of the character described, the combination with means for feeding a covered metal strip and cutting it into blanks, of a female die having a deep central recess and having a recess above and at each side of said central recess, a central 20 male die and side male dies arranged to enter said central recess, other side male dies adapted to enter the recesses at the side of said central recess, and means for successively operating said male dies to first impart an initial bend to the ends of each 25 blank and afterward impart a U-shaped bend to the body of the blank and fold inwardly the initially bent ends onto the inner face of the blank.

4. In a machine of the character described, the combination with means for feeding a strip, of means for severing said strip into blanks, a female die, a central male die, a pair of independently operable side male 30 dies at each side of said central male die, and means for successively operating the outermost of said side male dies, the central male die and the innermost of said side male dies to first partially fold the ends of each blank, then impart a U-shaped bend to the body of 35 the blank and finally complete the folding of the partially folded ends of the blank upon the inner face of the body thereof.

5. In a machine of the character described, the combination with means for feeding a strip, of means for severing said strip into blanks, a stationary female die having a central deep recess therein to impart a U-shaped bend to the body of each blank and having at the sides of said central recess walls provided each with a seat at its top for the partial upward folding of the ends of said blank, a central male die adapted to force the body of the blank into the deep 40

cess of the female die, relatively movable 65 side male dies for forcing the ends of said blank into said seats at the top of the walls of the female die to bend upwardly the ends of said blank, and means for reciprocating said side male dies that bend the ends of 70 the blank in advance of the reciprocation of the central male die.

6. A machine for forming a channel-shaped body having its ends folded inwardly toward each other, comprising a single female die having a deep central recess for imparting a bend to said body and having at each side of said central recess a recess and a male die adapted to impart an initial upward bend to the corresponding end of 80 said body, and male die mechanism having a central portion adapted to force said body down into said central recess and having side portions movable relatively to said central portion and adapted to complete the 85 folding of the ends of said body inwardly onto said body.

7. A machine of the character described, comprising a female die having a deep central recess therein to impart a U-shaped bend 90 to the body of a blank and having at the sides of said central recess stationary walls provided each with a shoulder at its top and with an upstanding lip outside said shoulder, a male die provided with a central portion 95 adapted to force the body of each blank into the deep recess of the female die and provided with side portions movable relatively to said central portion and adapted to turn upward the ends of the blank and to force 100 the ends of said blank downward and inward against the inner face of said blank.

8. A machine of the character described, comprising a female die having a deep central recess therein to impart a U-shaped bend 105 to the body of a blank and having at the sides of said central recess stationary walls provided each with a shoulder at its top and with an upstanding lip at the outer portion of said shoulder, male dies formed of separably movable parts and having outer side portions for turning upward the end portions of said blank and provided with other portions between said side portions adapted to force the body of the blank down and into 110 the deep recess of the female die and to complete the inward folding of the ends of the blank against the body thereof, and means for reciprocating said outer male dies in advance of the reciprocation of the male die 115 portions between them.

9. In a machine of the character described, the combination with mechanism for feeding a metal strip, of means for straightening the strip located in advance of said feeding mechanism, a support for the coiled strip located in advance of said straightening means, and means whereby as the weight of 120

the coiled strip decreases the pressure of the straightening means will be increased.

10. In a machine of the character described, the combination with mechanism for feeding a metal strip, of means for straightening the strip located in advance of said feeding mechanism, a support for the coiled strip located in advance of said straightening

mechanism, a spring for sustaining said supporting means, and a screw for adjusting the tension of said spring whereby the pressure of the straightening mechanism will be increased as the weight of the coiled spring decreases.

FRANK J. KOTZICH.
